UNITED STATES PATENT OFFICE

153,614

DESIGN FOR A SPINNING AERIAL
CARGO TOY

David W. Main, Denver, Colo.

Application June 18, 1947, Serial No. 139,789

Term of patent 14 years

(Cl. D34—15)

To all whom it may concern:

Be it known that I, David W. Main, a citizen of the United States, residing in the city and county of Denver and State of Colorado, have invented a new, original, and ornamental Design for a Spinning Aerial Cargo Toy, of which the following is a specification, reference being had to the accompanying drawing, forming part thereof.

In the drawing:

Figure 1 is top plan view of a spinning aerial cargo toy, showing my new design;
Figure 2 is a bottom plan view thereof;
Figure 3 is a side elevation thereof;
Figure 4 is a front elevation.

I claim:
The ornamental design for a spinning aerial cargo toy, as shown.

DAVID W. MAIN.
